UNITED STATES PATENT OFFICE

REUBEN C. BAKER, OF COALINGA, CALIFORNIA, ASSIGNOR TO BAKER OIL TOOLS, INC.,
A CORPORATION OF CALIFORNIA

CORE DRILL

Application filed January 31, 1928. Serial No. 250,829.

This invention relates to deep well drilling equipment and particularly pertains to a hollow rotary drill for drilling oil wells.

Hitherto, drill bits utilized in drilling wells by the rotary method were designed to act over the entire end area of the bore when sinking a well and advance the bore by pulverizing all of the formation encountered. This was necessary because the cuttings were removed by circulating a fluid downwardly through the drill pipe to the point of operation, and thence upwardly around the pipe to the surface. Therefore, the cuttings had to be sufficiently pulverized to permit them to be elevated by the fluid.

It is the principal object of the present invention to provide a generally improved well drilling apparatus by providing a rotary drill capable of advancing a bore through formation by pulverizing but a portion of the end area of the bore, the drill also being capable of recovering samples of the formation being penetrated.

In carrying out the invention into practice, I provide a hollow rotary drill having a drilling bit designed to pulverize an annular section at the perimeter of the end of the bore, permitting the center formation to advance upwardly through the drill. A fluid is circulated downwardly through the drill to elevate the cuttings. The circulating fluid also has access to a certain extent to the core passing upwardly through the drill pipe so that finely divided particles thereof will be carried to the surface. By pulverizing but a portion of the end area of the bore when advancing through formation, the drilling effort will be minimized and consequently the drilling will be expedited. Also, by causing the center portion of the formation being penetrated to pass upwardly in the drill pipe, samples of the formation being penetrated will be recovered for inspection when the drill pipe is removed from the well. This is advantageous as it permits analysis of the different formations encountered which is of a particular help to geologists in determining the presence of oil.

One form which the invention may assume is exemplified in the following description

and illustrated by way of example in the accompanying drawings, in which:

Fig. 1 is a view in side elevation of a drill embodying the preferred form of my invention.

Fig. 2 is a central vertical section through the same showing it penetrating into formation.

Fig. 3 is a transverse section taken on line III—III of Fig. 2.

Fig. 4 is a transverse section taken on line IV—IV of Fig. 2.

Referring more particularly to the accompanying drawings, 10 indicates a cylindrical hollow drill head having a threaded upper end 11 whereby it may be connected to a drill pipe. The lower end of the head is enlarged and is interiorly threaded as at 12 so that it may be threaded onto a drill barrel 14. This drill barrel is tubular and at its lower end it is exteriorly threaded to receive a drilling shoe or bit 15.

This drilling bit is formed with a cylindrical body portion 16 interiorly threaded so that it may be threaded onto the lower end of the drill barrel 14. At its lower end the body portion 16 of the drilling bit is formed with a plurality of cutting teeth 17 arranged in a circle about the center of the bit. Such a drilling bit is described and claimed in a co-pending application entitled Drilling shoe, filed April 27, 1927, Ser. No. 186,908. It will suffice to say that by arranging the teeth in a circle substantially equal in exterior diameter to the diameter of the bore, when revolved the shoe or bit will cut away a circular section at the perimeter of the bore, leaving a central core or section of formation not pulverized.

Arranged interiorly and concentric to the drill barrel is a core tube 18. This core tube extends the entire length of the drill barrel and is relatively fixed thereto. As illustrated in the drawings, the exterior diameter of the core tube is less than the interior diameter of the drill barrel so that an annular passageway will be formed between the drill barrel and the core tube to permit circulating fluid pumped downwardly through the head 10 to be discharged downwardly between the drill

barrel and core tube to both lubricate the cutting teeth 17 and to wash away the cuttings.

As before stated the drill barrel and core tube are relatively fixed together. This I 5 accomplish by cutting aligned slots 19 in the drill barrel and core tube at spaced intervals. I enclose each slot with a sleeve 20 which is welded to the drill barrel and core tube, so as to firmly fix the two elements together and to 10 prevent communication between the annular space between the drill barrel and core tube and the exterior of the drill barrel. The slots, however, serve as circulation or wash openings between the interior of the core tube and 15 the space surrounding the exterior of the drill barrel. The slots as illustrated are arranged on diametrically opposed sides of the device and relatively staggered.

At its upper end the core tube is plugged as 20 shown in Fig. 2, while at its lower end it aligns with and abuts against a split core trap ring 21. This trap ring 21 is formed with a tapered exterior surface 22, which nests within 25 in tapered ribs 23 within the body of the drilling bit 16.

In operation of the device, it is constructed and assembled as shown in the drawings and run in the hole at the end of a drill pipe suitably connected to the drill head 10. It is then 30 revolved and a circulating fluid is pumped downwardly through the drill pipe. This circulating fluid will pass through the annular space between the drill barrel and core tube and will discharge between the ribs 23 35 in the drilling shoe and will lubricate the cutting teeth 17 and carry away the cuttings. After passing out of the drilling shoe, the circulating fluid will pass upwardly around the exterior of the drill barrel and seek the surface. 40

As the drilling bit penetrates the formation, it will cut away an annular space at the perimeter of the bore, leaving a central portion of a diameter substantially the same as 45 the interior diameter of the core tube 18. This unpulverized portion of the formation penetrated will pass upwardly through the split trap ring 21 and into the core tube 18 as the drilling bit advances through the formation. 50

As the wash or circulating slots 19 extend between the interior of the core tube and the exterior of the drill barrel, the circulating fluid discharging upwardly around the drill 55 barrel will have access to the material passing upwardly into the core tube. The circulating fluid will act to disintegrate a greater part of the softer formations by coming in contact with the core through the wash slots 19. 60 These softer formations and any finely divided substances will be carried to the surface by the circulating fluid and the drill can continue to advance through the formation until the drill bit becomes dull or the core tube 65 becomes filled with the harder parts of the

formation that will not be disintegrated by the circulating fluid.

It is obvious that by merely pulverizing but a portion of the end area of the bore, the drilling effort will be minimized and consequently 70 the drilling will be expedited. Also, the circulating fluid is delivered directly to the point of operation, fully lubricating the cutting teeth and rapidly carrying away the cuttings.

As the interior surface of the split trap ring 21 is serrated, the core entrapped within the core tube may be elevated to the surface when the drill is removed from the hole. This trap ring 21 pinches off the core and acts 80 to retain it within the core tube. After the drill has been brought to the surface, the samples of formation contained within the core tube may be removed for examination. This bringing of samples to the surface is important 85 as it aids geologists in determining whether or not the formations being penetrated are favorable to the presence of oil.

While I have shown the preferred form of my invention, it is to be understood that various changes may be made in its construction by those skilled in the art without departing from the spirit of the invention, as defined in the appended claims.

Having thus described my invention, what 95 I claim and desire to secure by Letters Patent is:

1. A well drill including a body having a longitudinally disposed chamber formed therein, said chamber being open at its lower end, a bit at the lower end of said body adapted to cut away an annular area at the perimeter of the bore leaving a portion of formation in alignment with the chamber of an area permitting it to enter the chamber 105 as the drill is advanced through formation, means permitting circulating fluid to be discharged downwardly through the body without gaining access to said chamber, said body having a plurality of comparatively large 110 openings formed therethrough at spaced intervals along its length exposing formation in the chamber to circulating fluid passing along the body exteriorly of the body.

2. A well drill including a body having a 115 longitudinally disposed chamber formed therein, said chamber having a closed upper end and an open lower end, a bit at the lower end of the body adapted to cut away an annular area at the perimeter of the bore 120 leaving a portion of formation in alignment with the chamber and of an area permitting it to enter the chamber as the drill is advanced through formation, said body having a passageway formed longitudinally therethrough separated from the chamber to permit circulating fluid to be discharged downwardly through the body to the bit, said body being formed with spaced open areas along 125 its length forming communication between 130

the interior of the chamber and the exterior of the body to expose the formation in the chamber to circulating fluid passing along the exterior of the body.

5 3. A well drill comprising a hollow drill barrel, a drilling bit fixed to the lower end of the drill barrel and adapted to cut away an annular area at the perimeter of the bore leaving a portion of formation at the center of the bore, a core tube fixed within the drill barrel and of a diameter less than the interior diameter of the drill barrel, the upper end of said core tube being closed, the lower end of said core tube being open and extending to a point adjacent the bit whereby it may be passed over the formation remaining at the center of the bore as the drill advances, a plurality of enclosed passageways spaced at intervals along the drill forming communication between the interior of the core tube and the exterior of the drill barrel to permit circulating fluid passing exteriorly of the barrel to gain access to the formation in the tube.

25 4. A well drill comprising a hollow head, a drill barrel threadedly connected at its upper end to said head, a drilling bit, said bit having a hollow cylindrical body portion threadedly connected to the lower end of the barrel, cutting teeth on the lower end of the bit adapted to cut away an annular area at the perimeter of the bore leaving a portion of formation at the center of the bore, a core tube of a diameter less than the interior diameter of the drill barrel, said core tube being fixed concentrically within the drill barrel with its lower end substantially in alignment with the lower end of the drill barrel whereby it may pass over the formation at the center of the bore as the drill is advanced, the space occurring between the barrel and the tube permitting circulating fluid to pass between the barrel and the tube to the bit, a plurality of enclosed passageways extending between the core tube and the drill barrel at intervals intermediate the ends thereof forming communication between the interior of the core tube and the exterior of the barrel to permit circulating fluid exteriorly of the barrel to gain access to the interior of the core tube, said passageways not communicating with the space between the tube and the barrel.

55 5. A well drill comprising a hollow head, a drill barrel threadedly connected at its upper end to said head, a drilling bit, said bit having a hollow cylindrical body portion threadedly connected to the lower end of the barrel, cutting teeth on the lower end of the bit adapted to cut away an annular area at the perimeter of the bore leaving a portion of formation at the center of the bore, a core tube of a diameter less than the interior diameter of the drill barrel, said core tube being fixed concentrically within the drill barrel

with its lower end substantially in alignment with the lower end of the drill barrel whereby it may pass over the formation at the center of the bore as the drill is advanced, the space occurring between the barrel and the tube permitting circulating fluid to pass between the barrel and the tube to the bit, a plurality of enclosed passageways extending between the core tube and the drill barrel at intervals intermediate the ends thereof forming communication between the interior of the core tube and the exterior of the barrel to permit circulating fluid exteriorly of the barrel to gain access to the interior of the core tube, said body portion of the bit having tapered radial ribs arranged at spaced distances apart, a trap ring having a tapered exterior surface nesting within said ribs in a position to align with and abut against the lower end of said core tube.
